HOLDER FOR A TELEPHONE INSTRUMENT

Fred Bohm, New York, N.Y., assignor to Robosonics Inc.,
Bronx, N.Y., a corporation of New York

Filed July 14, 1964, Ser. No. 80,867

Term of patent 7 years

(Cl. D26—14)

FIG. 1 is a left side, top and front perspective view of a holder for a telephone instrument, showing my new design;

FIG. 2 is a front elevational view; and

FIG. 3 is a left side elevational view, the right side being substantially a mirror image thereof.

The bottom and back, not shown, are substantially flat, unornamented surfaces.

The broken line showing of a telephone desk set and connecting bracket for supporting the holder for a telephone instrument is for illustrative purposes only.

The dominant features of my design reside in those portions shown in full lines with shading in FIGS. 1, 2, and 3.

I claim:

The ornamental design for a holder for a telephone instrument, as shown and described.
